UNITED STATES PATENT OFFICE.

WILLIAM J. KEMLER, OF PITTSBURGH, PENNSYLVANIA.

CLOSURE DEVICE.

Application filed August 5, 1922. Serial No. 579,825.

To all whom it may concern:

Be it known that I, WILLIAM J. KEMLER, a citizen of the United States, residing at Pittsburgh, in the county of Allegheny and 5 State of Pennsylvania, have invented new and useful Improvements in Closure Devices, of which the following is a specification.

This invention relates to closure devices, 10 and more particularly to a device specially adapted to be used in connection with salt and pepper shakers and for similar purposes.

One of the main objects of the invention 15 is to provide a device of the character stated which may be readily applied and removed and which can be produced at small cost. A further object is to provide a device of 20 this character which presents a neat appearance and can be applied to a shaker of standard type. Further objects will appear from the detailed description.

In the drawings:—

Figure 1 is a side view of a shaker, partly 25 in section, showing the device as applied;

Figure 2 is a section through the closure device.

The device is intended to be used in connection with a salt or pepper shaker *a* of 30 standard type provided with a bottom wall *b* having a central opening *c*. It is the common practice, after the shaker has been filled, to close this opening by means of a cork or other stopper inserted tightly into 35 the opening. This is very objectionable as it is frequently difficult to remove the stopper and it often happens that this stopper is forced into the shaker in the attempt to remove it. To avoid this very serious 40 objection I provide very simple and efficient means whereby this opening may be quickly and easily closed, the closure device being so constructed as to be readily grasped so as to be quickly removed when desired.

45 The device includes a button-shaped member *1* provided with an upwardly projecting inwardly curved peripheral flange *2*. Within member *1* there is secured in any suitable or preferred manner a resilient strip *3* of 50 steel or other suitable material, the end portions of which are bent upwardly to form resilient arms *4* which are of substantially flattened V-shape, the angles *4a* of these arms being directed outwardly. By

forcing arms *4* through opening *c* the closure device is readily secured in position, the arms springing outwardly above bottom wall *b* and pressing tightly against the upper edge of the surrounding wall of opening *c* so as to hold member *1* snugly against the underface of bottom wall *b*. This serves to effectually close opening *c* so as to eliminate possibility of leakage of the contents of the shaker. The rounded rim or flange *2* provides simple and efficient means for 55 permitting member *1* to be readily grasped for pulling the same away from bottom wall *b*, during which operation arms *4* are compressed inwardly toward each other so as to be drawn through the opening *c*. 60

It will be seen that I have provided very simple and efficient means for closing the openings provided in shakers and similar articles, this closure means being of neat and simple construction and capable of being produced at very small cost. 70

What I claim is:—

1. In combination with a shaker provided through its bottom wall with an opening, a member adapted to fit over said opening for 80 closing the same, and upwardly diverging resilient arms secured to said member for insertion through the opening, the arms contacting with the inner edge of the wall of the opening to hold said member pressed snugly against the underface of the bottom wall of the shaker. 85

2. In combination with a shaker provided through its bottom wall with an opening, a member of greater area than said opening and provided with an upwardly extending peripheral flange of arcuate cross-section adapted to fit snugly against the bottom of 90 said shaker around the opening, and a strip of resilient material having its bight portion secured to said member within and below the flange, the end portions of said strip being bent to provide upwardly projecting arms of flattened V-shape, the angles of said arms being directed outwardly, and the arms 95 pressing upon the wall of the opening and acting to hold the closure member pressed snugly against the bottom of the shaker, the cross-sectional curvature of said flange facilitating gripping of the closure member 100 for removal thereof. 105

In testimony whereof I affix my signature.
WILLIAM J. KEMLER.
